UNITED STATES PATENT OFFICE.

FRANCIS B. WALLIS, OF EVERETT, MASSACHUSETTS.

ELECTRIC SOLE.

SPECIFICATION forming part of Letters Patent No. 360,127, dated March 29, 1887.

Application filed August 30, 1886. Serial No. 212,185. (No model.)

To all whom it may concern:

Be it known that I, FRANCIS B. WALLIS, of Everett, county of Middlesex, and State of Massachusetts, have invented an Improvement in 5 Electric Soles, of which the following description, in connection with the accompanying drawings, is a specification, like letters on the drawings representing like parts.

This invention has for its object to provide an 10 "electric sole," so called, which may be either permanently connected with or detachably placed within a boot or shoe, or other article of foot-wear, or wearing-apparel.

The invention consists of an electro-therapeutic appliance constructed substantially as 15 hereinafter particularly set forth and claimed.

In the drawings, Figure 1 shows in top view a sole embodying this invention, the perforated top piece being removed. Fig. 2 is a 20 plan of the perforated top piece detached, and Fig. 3 is a vertical cross-section of a sole constructed in accordance with my invention.

A bottom layer or sole, A, upon which the permanent parts are placed, is made preferably of water-proof material, and cut to the desired shape. Upon this layer or sole is arranged in alternation a series of copper and zinc rings, a b, which rings overlap, and a 25 piece of absorbent material, c—such as sponge—is placed within the central opening of each of the rings, to absorb moisture from the person, to assist in producing galvanic action, or a current between the person and the metal plates. Additional voltaic couples may 30 be had by means of copper and zinc strips d d', connected to the rings a b, of opposite polarity, and arranged substantially as shown.

A perforated thin layer or sole, B, of sheep-skin or other suitable material, is then placed 40 upon the metal rings and strips and the sole A, thereby concealing them and presenting a smooth surface for the person, the perforations 2 and 3 made in such sole B permitting the moisture from the person to pass freely through 45 to and be absorbed by the absorbent material c.

It is obvious that, instead of making the

parts a b as rings, they may be of any other desired shape; and also, instead of placing the absorbent material at the central openings in the rings it may be placed at any other convenient point. 50

If desired, felt or any other bibulous material may be employed as the absorbing material.

The sole, constructed as described, may be 55 permanently attached to a boot or shoe as an inner sole, or it may be employed as a sock-sole, to be introduced when desired.

A small quantity of dilute acid may be supplied to the absorbent material, which, mingling with the moisture from the person, increases the current. 60

What I claim is—

1. An electro-therapeutic appliance composed of a layer or sole, A, a series of overlapping copper and zinc disks placed thereon, absorbent material, as described, placed in contact with the batteries and suitably saturated with acid, and a perforated top layer or sole, B, substantially as set forth. 70

2. An electric sole composed of a layer or sole, A, a series of overlapping copper and zinc disks placed thereon, absorbent material, as described, placed in contact with the disks, the metal strips d d', coupled with the disks, 75 and the perforated top sole, B, all substantially as set forth.

3. An electro-therapeutic appliance consisting of a layer or sole, A, a series of voltaic couples consisting of overlapping metal rings 80 and metal strips connected thereto, absorbent material placed in connection therewith, and a perforated top layer or sole, B, substantially as described.

In testimony whereof I have signed my name 85 to this specification in the presence of two subscribing witnesses.

FRANCIS B. WALLIS.
